UNITED STATES PATENT OFFICE.

ARTHUR B. CRUICKSHANK, OF LONDON, ENGLAND.

PORTABLE TROUSERS PRESS AND STRETCHER.

1,106,550.

Specification of Letters Patent. Patented Aug. 11, 1914.

Application filed May 1, 1913. Serial No. 764,955.

To all whom it may concern:

Be it known that I, ARTHUR B. CRUICKSHANK, a citizen of the United Kingdom of Great Britain and Ireland, and resident of 5 Chancery Lane Safe Deposit, Chancery Lane, London, England, have invented certain new and useful Improvements in Portable Trousers Presses and Stretchers, of which the following is a specification, such 10 as will enable others skilled in the art to which it appertains to make and use the same.

It has been proposed to use lengthwise slats and spring clips and also wide lengthwise boards and spring clips for pressing and stretching trousers, but their use is not satisfactory, as with these devices trousers can only be slightly stretched at their edges and little, if any, stretching can be done 20 in the central part of the trousers between the edges and, moreover, the wide lengthwise boards are by no means portable.

In my invention by the use of cross slats in conjunction with lengthwise slats pairs 25 of slats can be held apart and besides pressing and creasing the trousers the whole width of the trousers can be well stretched; cross slats can be made to grip the ends of trousers much better than the ends of lengthwise slats or boards can be made to do so as much greater local pressure can be obtained with cross slats, consequently when 30 the trousers are stretched or pulled tight by hand the tension can be maintained.

35 By the special construction which I employ for the ends of the cross slats the members of a pair of slats can be held together without shifting their position in relation to each other so that the press, with 40 the trousers in it, can be hung up without any danger of it coming apart.

I use any suitable means for holding the slats together in pairs under pressure such as spring clips, or clamps, but preferably 45 the spring clips of special construction hereinafter described which will not slip.

My portable trousers press and stretcher comprises four pairs of slats, two pairs being lengthwise or side slats and two pairs being 50 cross slats and means, preferably spring clips, and by preference the spring clips hereinafter described, for holding each pair of slats together and pressing on the trousers, both legs of a pair of trousers being 55 pressed at the same time.

By preference the ends of the cross slats cross the ends of the lengthwise slats and preferably project beyond them, when in position on the trousers, the ends of the lengthwise slats butting up against and pressing against the sides of the cross slats, in this manner the lengthwise slats hold the cross slats apart and act as struts so that the trousers can be straightened and stretched, when in the press, by slightly pulling their ends through the cross slats, the spring clips yielding sufficiently for this purpose and the tension put on the trousers is thus maintained and the cross slats by their pressure on the trousers serve to keep the lengthwise slats apart, or the lengthwise slats might cross the ends of one or both pairs of the cross slats by making slight recesses in the lengthwise slats, near their ends, to take the ends of the cross slats; in this case long spring clips passing over the lengthwise slats might be used to hold the cross slats together.

By preference I construct the ends of one cross slat of the upper pair of cross slats 80 with pins or projections and the ends of the other cross slat of the same pair with holes or recesses to take the said pins or projections so that a pair of slats can be held together without any possibility of their 85 members shifting either sidewise or lengthwise, and the press can be hung up with the trousers in it, without any fear of its coming apart. I may also use the same construction for the lower pair of cross slats. 90

I preferably use spring clips (say ten) 95 of the kind constructed with one arm longer than the other, the end of the longer arm being so bent as to prevent it from slipping backward when the bent end is passed over the inner edge of a slat, or I may use spring clips constructed with a hole or recess in one or both of their arms and provide the slats with pins or projections to take the holes or recesses in the spring clips, or I may construct the spring clips with a pin or projection (projecting inwardly) on one or both of their arms and provide the slats with holes or recesses to take the said pins or projections on the spring clips. 100 105

I preferably furnish the press with means for hanging it up, such as a loop or ring which may be conveniently attached to one of the upper cross slats by means of a screw eye.

My portable trousers press and stretcher is very light and packs in a small compass when not in use and it can be hung up anywhere without the least danger of its coming apart or of any of the springs getting adrift, and trousers can be put in the press or taken out of it very quickly and it is inexpensive, it occupies a very small space when not in use and takes trousers of any width.

I will now describe my invention with reference to the accompanying drawings, in which:—

Figure 1 illustrates a trousers press and stretcher embodying the invention; Fig. 2 illustrates a perspective view showing two of the clamping slats in detached relation to each other; Fig. 3 illustrates a diagrammatic view illustrating a modification; Fig. 4 illustrates a detail view of a modification showing the clamp for retaining the modified construction in place; Fig. 5 illustrates a view in elevation of a clamp; Fig. 6 illustrates a side elevation of a clamp applied to fragments of slats, the same embodying a further modification; Fig. 7 illustrates a clamp in elevation and plan to be used in connection with a pin shown applied to the slat; and Fig. 8 illustrates a perspective view of the form shown in Fig. 7.

Fig. 1 shows a press and stretcher applied to a pair of trousers and illustrates an example of how the sets of slats keep each other apart and thereby maintain any stretch put into the trousers when the device is placed and held thereon, the slats at the same time exercising the requisite pressure. In this example the two pairs of cross slats at the top and bottom form one set and are lettered *a* while the two pairs of lengthwise slats form the other set and are lettered *b*. The slats of each pair are held together by spring clips *c* of which an enlarged view is shown in Fig. 5. One slat 45 of the upper pair of cross slats is provided with two pins *e* while the other slat of the same pair has holes formed in it to receive the pins, an enlarged view of this pair of slats is shown in Fig. 2 where the holes are lettered *f*.

When the press and stretcher is in position upon the trousers it can, with the trousers in it, be hung up in any convenient place by means of the loop and screw eye *d*. It will be observed that the ends of the slats *b* fit close up to the sides of the cross slats *a* and thereby keep the two pairs of cross slats apart, while the cross slats by means of their hold upon the trousers keep them

stretched sidewardly and thereby keep the two pairs of lengthwise slats apart.

Fig. 3 shows diagrammatically a modification in which the lower pair of the cross slats, which are here lettered *a'* have their ends shaped to fit recesses in the sides of the lengthwise slats *b*. Fig. 4 being an enlarged view of the meeting of the cross slats and the lengthwise slats shown in Fig. 3 and illustrates how a spring clip *c'* can be placed over the lengthwise slats to engage pins *g* on the cross slats, the said pins serving to keep the clip from accidental displacement.

Fig. 6 shows a modified form of a clip *c''* provided with pins *h* adapted to take into holes in the slats to which it is applied. This example shows rivet-like pins but any suitable projection such as pieces stamped or pressed out of the clip itself, will answer the purpose.

Figs. 7 and 8 show a clip *c'''* like that shown in Fig. 6 but furnished with holes adapted to fit over projections *i* on the slats.

It will be obvious that all the clips shown are provided with means to prevent displacement when fitted to the slats and while any means for that end may be used I generally prefer to use a clip of the type shown in Fig. 5 which is shaped to be readily placed over a pair of slats and is not likely to be accidentally displaced therefrom because of its projecting bent end.

It will be seen from the above description that as soon as the clips or other clamping devices are removed from the slats, the latter are quite free because they are in no way held together and the invention must therefore not be confused with that form of trousers press and stretcher in which two open frames are formed of slats screwed or cottered together between which frames the trousers are pressed.

What I claim and desire to secure by Letters Patent is:—

A trousers press and stretcher comprising pairs of slats adapted for engaging the edges and the top and bottom portions of trousers, clips for holding the pairs of slats in clamped relation to the trousers, the said slats at the sides of the trousers having their ends abutting the sides of the slats near the ends of the trousers.

In witness whereof I have hereunto set my hand in presence of two witnesses.

ARTHUR B. CRUICKSHANK.
